WALL CONSTRUCTION

George H. Ellis, St. Paul, Minn., assignor to
The Insulite Company, Minneapolis, Minn., a
corporation of Minnesota

Application October 20, 1930, Serial No. 489,987

9 Claims. (Cl. 72—101)

This invention relates to improvements in building construction, particularly to methods of applying facing elements or boards in the construction of the walls of buildings. The methods 5 may be applied in relation to studdings, or to floor stringers, and the facings are ordinarily covered with plaster, cement or stucco. The invention also includes means for decreasing heat losses at the joints, and means for reducing to a minimum buckling of the facing sheets, and fracture 10 of plaster coatings thereon.

It is well known that wood or synthetic materials absorb water and expand, and that the largest amount of expansion takes place before the 15 plaster is applied and that considerable expansion takes place after the application of plaster. There is also unequal expansion respectively of those portions which receive and do not receive plaster. One very objectionable practice has 20 been to "butt" the edges of the boards. When thus butted, the boards buckle, and the plaster cracks. It has also been the practice to lay a plurality of boards with the joints of the boards in a horizontal relation to the studding or trans- 25 versely thereof, and with the greater portion of the joint lying unsupported between the supports. A feature of the present invention is the arrangement of the joint longitudinally of the supports or studdings, so that the studding acts both as 30 a backing and support throughout the entire length of the joint, and prevents heat losses at the joint.

Among the objects of this invention are to provide means for compensating for expansion so 25 that the boards will not buckle or be injured, and so that cracking of the plaster is reduced to a negligible minimum.

Heretofore it has been the practice to use material which was overlapped to form an expansion joint, and also to have these joints arranged 40 perpendicularly to the long dimension of the studding, generally horizontally. An object of the present invention is to reduce heat losses by eliminating joints, the major portions of which 45 are unsupported, and to provide a construction in which all joints overlie or appear at the studding, and in which the studding may be said to cooperate to prevent heat losses, and in which the joints are so constructed (or in which the elements are so connected at the studding) that the 50 boards can slide on their supports at the joint. The present invention may be, in part, considered an improvement over the invention of my prior Patent No. 1,725,787.

55 Features and advantages of the invention will

be pointed out in the description of the drawings forming a part of this application, and in said drawings

Figure 1 is a perspective view illustrating one embodiment of the invention; 60

Figure 2 is a plan section on line 2—2 of Figure 1;

Figure 3 is a face view of one form of open-work sheet-fastening means;

Figure 4 is a face view of a portion of a wall 65 structure illustrating the application of another form of sheet-fastening means;

Figure 5 is a face view of a wall structure showing the application of a third form of sheet-fas- 70 tening device; and

Figure 6 is a plan section on line 6—6 of Figure 5.

Referring to the drawings: Numerals 1, 2 and 3 indicate studdings, or other suitable supports, only three of which are necessary to illustrate 75 one of the important features of the invention. Numeral 4 indicates a sheet of any suitable material which has opposite edges or margins respectively indicated at 5—6, overlappingly engaging the studdings 1 and 3. The middle of the sheet 80 in secured by suitable fastenings 7 to an intermediate studding 2. The sheet is thus secured at its midpoint and is capable of expanding in opposite directions from this point of attachment, the opposite ends 5 and 6 being slidably sup- 85 ported upon the studdings for expansion movement. Sheet 8 has its edge 9 also overlappingly engaged with the studding 1 and it is understood that this sheet is also connected at its middle portion to an intermediate studding or support by 90 devices the equivalent of device 7. Sheet 10 has its edge 12 slidably overlappingly engaging the studding 3 and connected to an intermediate studding like the other sheets. The sheets 4, 8 and 10 are, therefore, arranged so that they can ex- 95 pand from their midpoint outwardly. The ends 5 and 9 are spaced apart as are also the ends 6 and 12. Thus, by having the edges of adjacent sheets spaced apart, channel-like joints are provided, and the bottom of each channel is formed by a support. 100 In this way, each sheet is fastened at a point between its ends to an intermediate studding, leaving those portions of each sheet which lie at opposite sides of the fasteners, free to expand in opposite directions, the contiguous ends of adja- 105 cent boards being spaced apart sufficient to allow for such expansion.

It will be noted that each slab, or sheet, or facing element, is connected intermediate its joint-forming edges to at least every second sup- 110

port so that it may expand freely in a direction transverse to the joint. It is conceivable that the board may engage and be slidable under expansion effects against a plurality of supports lying at each side of its point of positive attachment to one of the supports which lies intermediate the joint-forming edges. The invention is not limited to the number of supports against which a given facing element may slide. The gist of this feature of the invention is the positive connection of a sheet in a manner to allow it to expand in opposite directions from the point of attachment, and in having channel-like joints which permit an increased depth of plaster, but which are formed by the support and the overlapping of contiguous boards on this support.

Means, which per se is a feature of this invention, is provided for securing contiguous but spaced ends of the boards against motion away from the studdings, but in a manner not to interfere with their expanding motions. These securing means or devices engage the board under compression, or frictionally, and are arranged across the joints. The fastening device illustrated in detail in Figure 3, and applied in Figures 1 and 2, is known as a "pretzel", and as before stated, this specific form of device is an important feature of the invention.

Referring to Figure 3, the device is composed of a single piece of wire bent upon itself as at 20 in a manner to provide surface contacting portions curved and straight, and to provide elongated arms 21-22 terminally bent to provide loops 25-26. In this instance, the loop 26 is an open one, while the loop 25 is closed, and an extension is provided which crosses and engages the elements 21-22. The extension has a portion 28, nail-receiving loop 30, and portion 31. In applying the device, the bend portion 20 engages one of the boards, while the loop portions 25-26 engage the opposite board, and the fastening device 35 maintains the frictional contact between the "pretzel" and the marginal portions of contiguous boards, and this fastening device is attached only to the support. The fastening devices 35 are not driven with sufficient force to pull the loop 30 downwardly into the channel, because if this were done, the "pretzel" would not only be deformed and its contact efficiency impaired, but it might interfere with the expanding motions of the sheets at the joint. The open work construction of the "pretzel" permits plaster to adhere to it, and to those portions of the sheet within the loop confines. The plaster is indicated at 37 in Figure 2. The "pretzel" is so formed that plaster can pass through it to form bonds with those portions of the sheets exposed through it, and plaster also adheres to the "pretzel", which thus functions to permit expansion before and after plaster is applied, and to reinforce the plaster over the joint, reducing to a minimum cracking, partly because the plaster can engage the board material within the confines of the reinforcing element. It will be noted that the long axis A of the device is arranged substantially perpendicularly to the joint so that the parts 21-22 lie in direction of expansion and therefore do not unduly interfere with it.

Inasmuch as a sheet used in the manner set forth may be said to be weakened in proportion to the strength of the sheet, it may be said that the across-the-joint fastening element compensates for loss of strength at the joint, due to the separated condition of the sheets thereat. The joint formed herein is then as strong as a joint

formed by overlapped sheets, and has the added value of being vastly more heat-leak-proof, than a joint which is substantially unsupported throughout its length because it is located intermediate of the supports. Tests show that a joint formed by the use of wire open-work elements is substantially stronger than a joint formed by overlapping contiguous boards. Therefore, this joint is a feature of the invention, aside from the use of an open-work fastening device, in that there are no horizontal joints or joints which lie intermediate of the supports.

Another feature, which is claimed herein, irrespective of the fastening devices, is the manner of forming the channel-like joints, using the support as a backing, and channel-forming element, and having the joints at the support, as distinguished from that type of joint having its major portions located at points intermediate of the supports to permit of greater heat losses over that very much larger area which lies between the supports. In house building practice, the sheets 4 extend from floor to ceiling. Moreover, the vertical joints only lie over every other studding and thus the total number of joints are also reduced in this way. An important feature.

In Figure 4, a modification of sheet-fastening means has been illustrated. This fastener is formed from a single piece of wire which is given a sinusoidal configuration, to provide opposingly arranged loops respectively indicated 50-51. The loops 50 engage the board 4 and the loops 51 engage the board 8, the material being looped between the arcuate portions as at 52 to provide openings to receive fastening devices 53 which pass into the studding 1. This wire element can be made to extend the full vertical length of the joint in a single piece or a plurality of the devices may be arranged in spaced relation as in the embodiment of Figure 1.

Another modification is illustrated in Figures 5 and 6. In this form, the sheet-fastening means is constructed of expanded metal. The device includes a body portion 60, arched as at 61 and having openings 62 therein for the reception of fastening devices 63, which are driven into the studding 1. Integral with and lying at opposite sides of the body portion 60 are the expanded metal portions 64-65 respectively frictionally engaging the outer faces of sheets 4 and 8. It is one of the objects of this invention to provide a fastening means which will not interfere with the expansion of the sheet in direction of the arrows A-B, and to this end the body portion is arched as at 61 so that in driving the fastening device 63, this portion will not be mashed sufficiently to occupy a position shown in dotted lines at 67, and thus interfere with expansion motions of the sheets. This is a valuable feature of the invention. The action of this device in securing the parts is substantially the same as that before described, the expanded metal portions 64-65 providing an open work structure through which the plaster 68 can pass and bond with the outer surface of the boards.

In all forms of the invention, open-work joint-crossing elements are employed. In Figures 1, 2 and 3 the open work is obtained by manipulating to provide a series of bends and/or loops; in Figure 4 by reversely bending the wire to give it sinusoidal form; and in Figure 5 by using expanded metal.

I claim as my invention:

1. A building structure comprising spaced supports, sheets of facing material laid against the

supports and having edges of adjacent sheets spaced apart to provide a channel-like joint the bottom of which is formed by the support, means positively securing each sheet only to a support which is intermediate the joint-forming supports and the joints, to permit free expansion of the board in opposite direction from its point of attachment, elements arranged across the joints engaging the faces of and securing the sheets against movement outwardly from the supports but permitting expansion in direction transversely of the joint, said elements being so formed that plaster can pass through them to form a bond with portions of the sheets, and with portions of the securing elements, means operatively attaching the elements only to the supports, and a plaster facing for the sheets passing through the securing elements, entering the channel-joint, and forming a bond with the sheet surfaces and with the elements.

2. A fastening device for the purpose described formed from a single piece of wire bent to provide elongated substantially parallel portions terminating in loops, one of the loops having an extension crossing said portions and having a loop therein which lies intermediate the parallel portions.

3. A fastening device for the purpose described formed of a single piece of wire and bent to provide elongated parallel portions terminating in loops, and with an extension of one of the loops crossing the parallel portions and having a loop therein which lies intermediate the parallel portions.

4. A building structure comprising spaced supports, sheets of expandable material laid against the supports to provide open joints on the supports, nails securing the sheets only to supports other than those on which the joints are formed to permit free expansion and sliding of the sheets on those supports on which the joints occur, and a series of fastening devices arranged across the joint and engaging the faces of the sheets in a manner to prevent motion of the sheets outwardly from the supports but not to interfere with the sliding motions aforesaid, each composed of a single piece of wire bent to provide an open work structure including elongated portions which substantially extend in direction of the sliding motion of the sheets, and which has a loop in opposition to the joint, and a fastening device passing through the loop and through the joint to secure the device to the studding without interfering with the sliding motion.

5. A building structure comprising spaced supports; sheets of expandable material laid against the supports to provide open joints on the supports, nails securing the sheets only to supports other than those on which the joints are formed, to permit free expansion and sliding of the sheets

on those supports on which the joints occur, and a series of fastening devices arranged across the joint and engaging the faces of the sheets in a manner to prevent motion of the sheets outwardly from the supports but not to interfere with the sliding motions aforesaid, each comprising a single piece of wire bent to provide an open work structure including elongated portions which substantially extend in direction of the sliding motion of the sheets, and which have loops, one of the loops having an extension crossing elongated portions and having a loop which lies intermediate said portion and in opposition to the joint, a fastening device passing through the last mentioned loop and through the joint to secure the device to the studding without interfering with the sliding motion, and a plaster facing for the sheets which forms a bond with the fastening devices and enters the joint.

6. A fastening device for the purpose described formed from a single piece of wire bent to provide a series of reverse bends at least one of which forms a closed loop for receiving a fastening device by which the article is attached.

7. A fastening device for the purpose described formed from a single piece of wire bent to provide a series of reverse bends at least one of which forms a closed loop for receiving a fastening device by which the article is attached, the bends being disposed at opposite sides of that loop which is designed to receive the fastening device.

8. A building structure comprising spaced supports, sheets of moisture absorbable material laid against the supports in such manner that no joint bridges the supports, and so that open joints are only formed on non-consecutive supports, and in a manner to permit free expansion and sliding of the sheets on those supports on which the joints occur, means positively securing each sheet only to one support which is intermediate of the supports on which the joints are formed, and means arranged across each joint and engaging the faces of the sheets to prevent outward motion but not to interfere with sliding motion.

9. A building wall structure comprising spaced supports, sheets of moisture absorbable material laid against the supports in such manner that no joint bridges the supports, and so that open joints are only formed on non-consecutive supports, and in a manner to permit free expansion and sliding of the sheets on those supports on which the joints occur, each sheet being of a height to extend from floor to ceiling, means positively securing each sheet only to one support which is intermediate of the supports on which the joints are formed, and means arranged across each joint and engaging the faces of the sheets to prevent outward motion but not to interfere with sliding motion.
